FLOW VALVE

Wilbur R. Godsey and William Horn, Kilgore, Tex., assignors to Oil Lift Supply Company, Kilgore, Tex., a corporation of Texas

Application April 15, 1940, Serial No. 329,693

9 Claims. (Cl. 103—233)

This invention relates to valves used for unloading or flowing a well by what is known as the gas lift method, which is employed where the formation pressure is insufficient to flow the liquid up through the well to the surface of the earth and in which, therefore, some form of pumping or lifting operation is necessary to produce the flow.

In the gas lift method of flowing wells, gas under pressure is forced either into the casing or into the tubing of a well to cause the flow. For example, the gas may be forced into the casing around the outside of the tubing and the tubing used for flowing the well, the gas pumped into the casing forcing the oil level down therein and up into the tubing until finally the gas will pass below the lower end of the tubing, and into the tubing to force the oil out of the tubing to the surface of the ground.

In many cases, however, it is desirable, if not necessary that the gas be admitted to the tubing at spaced points along its length and various types of valves have been devised for admitting the gas at spaced points along the tubing. One such type, known as a kick-off valve, is intended to admit gas under pressure from the casing into the tubing at a predetermined point to force the oil in the tubing above that point out of the top of the well, thus lightening the column of oil in the tubing. Such valves may be used at spaced points along the length of the tubing so that with a relatively low gas pressure it is possible to unload the tubing in stages.

The upper valves in such a system may be known as kick-off or unloading valves, but any valve in such a series may act as the flow valve. Thus, when the gas under pressure is admitted into the casing and serves to lower the level of liquid standing in the casing to a point below the uppermost valve, gas will then be admitted into the tubing at this point. The gas so admitted will lighten the column of fluid above this valve and if the valve remains open and the well pressure is insufficient to cause the fluid to flow into the tubing as fast as it is being unloaded by the gas entering through the uppermost valve, the oil above the uppermost valve will be unloaded and the uppermost valve should then be closed. The fluid level in the casing will then again be lowered by the pressure of gas in the casing and the process repeated through the second valve and so on until the lowermost valve is reached. However, if while gas is being admitted through any one of the valves the well pressure is sufficient to cause the well fluid to

enter the tubing as fast as it is being unloaded from the tubing, there will be a column of oil constantly rising past the valve through which the gas is entering. This column will be constantly aerated by that gas entering through that valve and the well will be kept flowing. The valve through which the gas is entering will in such instances be operating as a flow valve.

The object of the present invention is to provide a new type valve such as above referred to and one which will be simple to manufacture, easy to adjust, and efficient in operation.

One form of the invention is illustrated in the accompanying drawing in which:

Fig. 1 is a longitudinal section through the casing of a well showing the disposition therein of unloading and flow valves in accordance with this invention.

Fig. 2 is a longitudinal section through a section of the tubing shown in Fig. 1 illustrating the manner of mounting the valves thereon.

Fig. 3 is a side elevation of the structure shown in Fig. 2.

Fig. 4 is an enlarged longitudinal section through a flow valve constructed in accordance with this invention illustrating the same in open position.

Fig. 5 is a view similar to Fig. 4 but showing the valve in closed position.

Referring specifically to the drawing, 6 indicates a well casing and 7 a string of tubing therein, these parts being provided with the usual or suitable Christmas tree connections indicated as a whole at 8 for flowing off the oil and for admitting gas under pressure to either the casing or the tubing, according to the manner in which the apparatus is used.

At spaced points along the tubing, one section of which is shown in Figs. 2 and 3, a series of valves are placed, constructed according to the present invention. Each valve indicated as a whole at 9 is set at the top into a boss 10 which may be welded or otherwise secured to the tubing section and held at the bottom in a fixture 11 welded or otherwise secured to the outside of the tubing section. The boss 10 has a port 12 which connects the upper end of the valve casing with the interior of the tubing.

The valve comprises an upper cylinder 13 threaded to a screw connection 14 which is screwed into the boss 10 as indicated at 15. At its lower end the connection 14 is provided with a seat ring 16 cooperating with a tapered plunger valve 17 having a collar or shoulder 18 which stops against a ring 19 fixed in the cylinder 13,

and having a small port 20 therein. An inlet port 21 extends through the cylinder 13 at a point adjacent the valve 11. The valve stem 22 works through the ring 19 and at its lower end is reduced as indicated at 23 and threaded to receive nuts 24 working in a recess 25 in a coupling 26. A spring 27 is coiled around the stem 22 and is held in compression between the ring 19 and a washer 28 which rests upon a ferrule 29 supported by the nuts 24, the lower end of the cylinder 13 being screwed onto the coupling 26. A lower cylinder 30 is screwed at its upper end to the coupling 26. A plunger rod 31 is enclosed in the cylinder 30 and works at its upper end loosely through a hole 32 in the coupling 26 and also through a ring 33 fixed in the lower cylinder 30, with a collar 34 which stops against the ring 33 to limit the downward motion of the rod. A spring 35 is coiled around the plunger rod 31 in compression between the ring 33 and adjustable nuts 36 threaded on the lower end of the rod 31. The upper end of the plunger rod 31 bears against the lower end of the stem 23 when the stem 23 is in open position or is being closed, and the ring 33 is provided with a port 37 to connect the upper chamber in the cylinder 30 with the open lower end of the cylinder and hence with the space within the well casing.

Valve structures thus described are assembled in series at various selected points along the tubing 7, as above indicated, from some point below the static fluid level of the well to some predetermined point adjacent to the bottom of the well. The spacing and location of these valves depend on many factors, including the pressure of the gas supply available and the characteristics of the particular well.

In operation tubing carrying the valves referred to is lowered into the well and naturally the liquid in the well will rise in the tubing to the same level as in the casing. The gas under pressure will then be forced into the casing and will serve to depress the level of the liquid in the casing and cause the level in the tubing to rise until the level in the casing falls below the uppermost valve in the series. The valve 11 being normally open, gas in the casing will be forced through the port 21 into the valve, and thence through the passage 12, and will serve to lighten the oil above the valve and begin the unloading operation. This gas will be fed at a rate which will aerate but not necessarily fast enough to form a gas piston underneath the column of oil. If the well is capable of producing rapidly enough at this level to keep feeding the oil up through the tubing and prevent further lowering of the level in the casing, gas will continue to feed through said uppermost valve which will under such circumstances act as a flow valve. If, however, the well has insufficient capacity at such a high level to continue producing, the level in the casing would be forced down by the gas until the second valve is reached. During this time it is desirable that the valve be of such a nature that it will remain open until the level of liquid in the casing approaches the second valve. In other words, the uppermost valve should be hard to close or should require a relatively high differential between the pressure in the casing and that in the tubing at the valve.

After the closing of the first valve the flow should take place through the second valve in the same manner as previously in the first valve. This should continue until a level is reached at

which the well will produce as fast as it is being unloaded or until the level in the casing falls below the lowermost valve. In any case, moreover, the upper valves must not only be of such a nature that they will be hard to close, but they must also be of such a nature that at no time will the column of liquid above them be sufficient to cause them to reopen once they have closed.

Now the lowermost valve is termed a flow valve as distinguished from an unloading valve because its primary purpose is to keep the well flowing as distinguished from unloading the static column of liquid in the well. This lowermost valve should be set so that immediately when the differential becomes a little greater than it should be it will close and shut off flow of gas to the tubing. On the other hand, as soon as the differential drops by virtue of flow of oil into tubing from the well by any substantial amount, this valve should then again open and aerate the fluid to cause it to flow from the well.

In the valve which is being discussed here, the valve is normally held open by means of the spring which surrounds the valve element. The spring which surrounds the auxiliary plunger 31 has no direct effect on the valve at any time. Its only effect is to act against the force on the auxiliary plunger rod 31 that tends to close the valve. This valve would therefore normally stand open when the pressures within and without the tubing are equalized.

Now, assuming that the valve in question is the uppermost valve of a series of unloading valves, the valve would remain open until the liquid level in the casing is forced down past this valve. At this point the gas would start entering through the valve and this gas would aerate the column in the tubing above the valve so as to assist in unloading this column. Assuming that the well flow is insufficient to maintain this level in the casing, the level in the casing would continue to be lowered until a point is reached adjacent the next lower valve. During this time the differential on the uppermost valve will be increasing because the casing pressure will remain the same and the column of liquid above the uppermost valve will be lightened and unloaded by the gas entering through this valve. This increase in differential will cause a greater flow through the uppermost valve and the throttling effect at the port 21 of this valve will cause a reduction of the pressure within the upper portion of the cylinder 13. Since the upper and lower portions of cylinder 13 are in communication through the port 20 and there is no substantial flow through port 20, the pressure in the lower part of cylinder 13 will also be lowered to the same value as that in the upper portion. The pressure in the cylinder 13 normally acts on an area equal to the cross section of the auxiliary plunger 31 tending to hold the same against movement in a direction to close the valve, and as this pressure drops its effect on this plunger tending to hold it in such position decreases. At the same time there will be a constant pressure acting on the area of the plunger 31 tending to close the valve. As this differential increases the tendency for the valve to close will increase. The force tending to close the valve however will be opposed not only by the spring surrounding the valve element but also by the spring surrounding the plunger 31. The valve will thus remain open until a sub-

stantial differential of pressures is established. The valve will then move quickly to a closed position and when the valve is seated there will be a differential of pressures established between the interior of the tubing and the cylinder 13. The pressure in this cylinder will become equal to casing pressure, whereas a pressure relatively much lower will prevail in the tubing. This differential of pressure will serve to overcome the spring surrounding the valve element and keep the valve closed. In the meantime, however, the rise of pressure in this cylinder will have removed the differential of pressure acting upon the area of the auxiliary plunger 34 and the auxiliary plunger will under the influence of its spring 35 return to the position which it occupied when the valve was open. It will now be seen that the only forces tending to open the valves will be those due to the pressure in the tubing and the spring surrounding the valve element, whereas the only force holding it shut will be the casing pressure. This will make the valve hard to open once it is closed. That is, the pressure in the tubing must rise until it exerts on the valve element enough force so that taken with the force exerted by the spring around the valve element it will overcome the casing pressure. Thus, the tension on the spring 27 alone will determine the opening differential whereas the closing differential is determined by the tension on both springs 27 and 35.

The unloading valve will thus be hard to close (it will require a high differential to close it) and hard to open (it will require a low differential to open it). The other unloading valves will be similarly adjusted.

The flow valve at the lower end of the string of tubing will be adjusted so that it will close when the differential becomes a little greater than it should be (that is, when the amount of liquid being fed into the tubing becomes less than that discharged) but when the differential is reduced a relatively small amount as when the fluid again begins to rise in the tubing, the valve will reopen to discharge this fluid. This is accomplished with the same type of valve as used for the unloading valves, merely by varying the adjustments on the two springs. In the flow valve, the springs surrounding the valve element would be placed under a greater tension than in any unloading valve, whereas the spring surrounding the auxiliary plunger would be left under relatively smaller tension. With this adjustment the springs surrounding the valve element would have a greater effect tending to open the valve and this would increase the differential at which the valve would open, whereas the spring surrounding the auxiliary plunger would have less effect in retarding the closing of the valve, thus making the valve close at a smaller differential.

It will be seen therefore that a valve has been produced which can be very accurately regulated both as to its opening and closing characteristics and that the opening and closing characteristics may be adjusted independently of each other. It will further be apparent that a valve has been provided which is capable of use both as a kick-off or unloading valve and as a flow valve, and that this valve is capable of achieving all of the objects sought by this invention.

We claim:

1. In a gas lift apparatus for flowing wells, the combination of a well casing, a well tubing with-

5 in the same, and a gas inlet valve controlling the flow of gas from the interior of the casing into the tubing, said valve being provided with a resilient means to normally hold it in open position and with a pressure actuated plunger separate from and independently movable with respect to said valve element and adapted to act upon and close the same under predetermined conditions of differential of pressure between the casing and the tubing.

2. The combination of a well casing, a well tubing therein, and a gas inlet valve mounted on the tubing, within the casing, said valve comprising a reciprocating valve member, a spring coiled around said member and tending to open the same, and a pressure actuated plunger separate from and independently movable with respect to the said valve element and adapted to act upon and bear against said member and adapted to close the same under predetermined conditions of differential of pressure between the casing and the tubing.

3. In a gas lift apparatus for flowing wells, the combination of a well casing into which gas may be supplied under pressure, a well tubing within the casing, and a valve controlling the flow of gas from the casing into the tubing, said valve comprising a cylinder having a valve seat surrounding an outlet in one end thereof and a side inlet port, a reciprocating member in the cylinder cooperating at one end with said seat, a spring operatively connected to said member and tending to hold the same in open position, and a pressure actuated plunger separate from and independently movable with respect to the said valve element and adapted to act upon and bear against the other end of said member and tending to close the same when the differential pressure exceeds the resistance of the spring.

4. A valve for use in admitting gas under pressure into an upright liquid flow conduit comprising a member having a passage communicating with the interior of said liquid conduit, a movable valve element adapted to close said opening, resilient means for urging said valve element toward open position, and means separate from and independently movable with respect to said valve element and actuated by the differential of pressure between the interior of said liquid conduit and the gas being injected into said conduit to move and to thereby force said valve element to closed position against the tension of said resilient means when said pressure differential reaches a predetermined maximum.

5. A valve for controlling the admission of gas under pressure to an upright liquid flow conduit comprising a member having a passage communicating with the interior of said liquid conduit, a valve element movable to close and open said passage, a resilient means for constantly urging said valve element toward open position, means separate from and independently movable with respect to said valve element and actuated by the differential between the pressure within said liquid conduit and the pressure of the gas being admitted thereto when said valve element is in open position for itself moving and thereby causing movement of said valve element to closed position against the tension of said resilient means when said pressure differential exceeds a predetermined amount, and means in addition to said resilient means for resisting such movement of said pressure differential responsive means.

6. A valve for controlling the admission of gas

under pressure to an upright liquid flow conduit comprising a member having a passage communicating with the interior of said liquid conduit, a valve element movable to close and open said passage, a resilient means for constantly urging said valve element toward open position, means separate from and independently movable with respect to said valve element and actuated by the differential between the pressure within said liquid conduit and the pressure of the gas being admitted thereto when said valve element is in open position for itself moving and thereby causing movement of said valve element to closed position against the tension of said resilient means when said pressure differential exceeds a predetermined amount, and a second resilient means opposing such valve closing movement of said pressure responsive means.

7. A valve for controlling the admission of gas under pressure to an upright liquid flow conduit comprising a member having a passageway for admitting such gas to said conduit, a movable valve element adapted to close and open said passageway, a resilient member urging said valve element toward open position and adapted to move said valve element to open position whenever the differential between the pressure within said conduit and the pressure of the gas to be admitted thereto falls below a predetermined minimum, and means separate from and independently movable with respect to said valve element and subject to the pressure within said conduit and to the pressure of the gas being admitted to said conduit for engaging said valve element and moving the same to closed position against the tension of said resilient member when the differential between said pressures exceeds a predetermined maximum.

8. A valve for controlling the admission of gas

under pressure to an upright liquid flow conduit comprising a member having a passageway for conducting such gas to said conduit, a movable valve element subject when closed to the pressure differential between the interior of said conduit and said gas to retain said valve in closed position, resilient means urging said valve toward open position for opening said valve when said pressure differential falls below a predetermined minimum, means separate from and independently movable with respect to said valve element and in addition to said valve and subject to the pressure differential between the interior of said conduit and said gas when said valve is open to engage said valve and move it to closed position against the tension of said resilient means when the pressure differential exceeds a predetermined maximum, and means for varying the effect of said pressure differential on said last mentioned means to predetermine the maximum pressure differential at which said means will operate to close the valve.

9. In a valve for controlling the admission of gas under pressure to an upright liquid conduit comprising a member having a passage therethrough for the flow of such gas into said conduit, a valve element movable to close and open said passage, means acting upon said valve element to move the same to open position when the pressure differential between the interior of said conduit and said gas falls below a predetermined minimum, and other means separate from and independently movable with respect to said valve element for moving said valve element from open to closed position when said pressure differential exceeds a predetermined maximum.
